CIRCUIT CONTROL SYSTEM

George W. Nagel, Catonsville, Md., assignor to
Westinghouse Electric & Manufacturing Company,
East Pittsburgh, Pa., a corporation of
Pennsylvania

Application February 5, 1943, Serial No. 474,827

2 Claims. (Cl. 250—27)

My invention relates to circuit control systems, and in particular to means for initiating and interrupting current flow through a direct-current system by employing gas filled electrical discharge tubes embodying control electrodes.

By reason of their ability to both initiate and interrupt the flow of currents of even large magnitudes in electrical circuits of the alternating-current type, grid controlled gaseous discharge tubes in recent years have found a wide application. Their ability to control the flow of such large currents without the sparking, arcing, and other destructive effects which would result if the attempt were made to interrupt such currents through separable contacts of conventional prior art circuit breakers is, of course, one of the reasons for the increasing use of mercury arc tubes provided with igniter electrodes in electrical welding and similar fields. However, the property of gaseous electrical discharge tubes that, while they can be maintained in a substantially non-conductive condition indefinitely by applying proper voltages to their control electrodes, yet such electrodes lose their power to control current flow from a direct-current source through the tubes once the tubes have been rendered conductive, has largely prevented their employment for the control of currents of substantial size in direct-current circuits. However, I have devised a circuit arrangement by means of which a pair of grid controlled gaseous electrical discharge tubes is employed in such a way as to effectively initiate current flow whenever it is desired to do so in a direct-current circuit and to later stop the current flow in the same circuit even in the case of currents of very substantial magnitude.

It is, accordingly, one object of my invention to provide an arrangement of gaseous electrical discharge tubes having control electrodes for initiating and interrupting at will the flow of current in direct-current circuits.

Another object of my invention is to provide an arrangement of the type described in the preceding paragraph in which current flows in one of the discharge tubes only during the time that current flow in the circuit is in process of being reduced to zero, whereby the said discharge tube has a life in service many times greater than would be possible were it continually energized during the times when current in the circuit was either in a steady state of flow or a steady state of interruption.

Other objects of my invention will become apparent upon reading the following description

taken in connection with the drawing in which the single figure is a schematic diagram of a circuit embodying my invention.

Referring in detail to the drawing, a direct-current supply line has a positive wire 1 and a negative wire 2 and is connected to supply direct current to a load 3. The positive side of the load 3 is connected directly to the positive line wire 1 while its negative terminal is connected to the anode 4 of an electrical discharge tube 5 of the gaseous discharge type. The cathode 6 of the tube 5 is connected to the negative line wire 2. The discharge tube 5 is provided with a control electrode 7 which may have the form of a grid, or may be an igniter electrode dipping into a cathode comprising a mercury pool if the tube 5 is one of the widely used type described in Slepian and Ludwig Patent 2,069,283. It is substantially immaterial what type of control electrode arrangement is applied to the discharge tube 5 so long as proper arrangements are made to supply the control electrode with voltage of a type adapted to prevent the initiation of current flow between the anode 4 and the cathode 6 when they are supplied with operative voltage, and to initiate current flow between these two electrodes upon a predetermined change in the electrical condition of the control electrode 7.

The control electrode 7 is connected directly to one terminal 8 of a double-throw switch having a movable blade 9 which is biased to an intermediate position in which the switch stands on open circuit. The blade 9 is connected to the cathode 6 of the tube 5. The control electrode 5 is likewise connected through a resistor 11 to the negative terminal of a bias battery 12, the positive terminal of which is connected to the cathode 6. The negative terminal of the bias source 12 is likewise connected through a resistor 13 to the second pole 14 of the double-throw switch previously mentioned. The pole 14 is likewise connected to the control electrode 15 of a gaseous discharge tube 16 of the electrode-controlled type. The tube 16 may if desired be of the same general type as the tube 5, or may be of any of the types mentioned in discussing the tube 5. The anode 17 of the tube 16 is connected through a resistor 18 to the positive supply wire 1 and is likewise connected through a capacitor 19 to the anode of the tube 5. The cathode 21 of the tube 16 is connected through a capacitor 22 to the cathode 6 of the tube 5 and is likewise connected through a resistor 23 to the anode 4 of tube 5.

The voltage of the bias-source 12 has such a

value that when the switch blade 9 stands in the open circuit position shown in the drawing, the control electrodes 7 and 15 of the two tubes 5 and 16 are of such a potential relative to their cathodes as to prevent the initiation of current flow through either of these tubes when the voltage of the direct-current line 1, 2 is impressed between their anodes and cathodes. Thus we may consider that in the system shown in the drawing, both the tubes 5 and 16 are non-conductive; under this condition no current will flow through the load 3 from the lines 1, 2 or in any part of the circuit whatsoever. To initiate current flow through the load, the switch blade 9 is moved into contact with the terminal 8, thereby connecting the control electrode 7 of the tube 5 to the cathode 6. The tube 5 is of such a type that when its control electrode 7 and its cathode 6 are at the same potential, the voltage of the lines 1, 2 will be sufficient to initiate current flow from the anode 4 to the cathode 6 through the load 3. The switch blade 9 may then be released, if desired, so that its mechanical bias will return it to open circuit position, but current will still continue to flow through the load 3 and the tube 5 by reason of the well-known properties of gaseous electrical discharge devices. Such current flow continues until it is desired to interrupt it.

It will be observed that the capacitor 22 is shunted across the terminals of the gaseous discharge tube 5 and hence is charged to the relatively low voltage characteristic of the arc drop in a gaseous discharge tube. Thus the potential of the cathode 21 of the tube 16 is more positive than the potential of the positive terminal of the bias source 12, by the amount of the arc drop in tube 5, and so the control electrode 15 of the tube 16 is negative relative to its cathode 21 by the sum of the arc drop in tube 5 and the bias source 12, thereby insuring that the tube 16 remains non-conductive as long as the system is in the condition just described.

When it is desired to interrupt current flow through the load 3, the switch blade 9 is moved into contact with the terminal 14, thereby connecting the control electrode 15 to the left-hand terminal of the capacitor 22 and reducing the potential difference between the control electrode 15 and the cathode 21 to the comparatively small value existing between the plates of the capacitor 22, that is the arc drop in tube 5. As a result of this effective removal of the bias potential of source 12 from control electrode 15, the tube 16 is rendered conductive to current flow. It will be noted that while current flow continued through the load 3 and the discharge tube 5, the capacitor 19 had its right-hand plate connected to the positive line wire 1 and its left-hand plate connected to the anode of tube 5, which latter differed in potential from the negative line wire 2 only by the small arc drop through the tube 5. It will be evident, therefore, that the capacitor 19 stood charged to a voltage equal to that of the direct-current lines 1, 2 minus the small arc drop through the tube 5. Now when the tube 16 has been rendered conductive, as above described, by moving the switch blade 9 into contact with pole 14, the capacitor 19, charged nearly to the full voltage of the lines 1, 2, initially impresses its voltage between the anode 17 and the cathode 21 of the tube 16 and starts to discharge through that tube. This discharge can take place through two paths which are in parallel with each other; namely, through the resistor 23 as one path, and through the capacitor 22 from the cathode 6 to

the anode 4 of the tube 5 as the other path. Since the plates of the condenser 22 differ from each other only by the small arc drop of the tube 5, and the resistor 23 is given a comparatively large value, this means that almost the entire charge on the condenser 19 will flow through the tube 16 and, in a reverse direction, from the cathode to the anode of the tube 5. The capacitor 19 is by design made large enough so that this reverse current flow through the tube 5 will tend to exceed the current flowing from the anode to the cathode thereof through the load 3, thereby reducing the net current flow from the anode to the cathode of the tube 5 to zero which causes deionization of the space between the anode 4 and the cathode 6. The tube 5 having thus been rendered non-conductive, the current previously flowing through the load 3 now is forced into the path through the condensers 19 and 22 and the tube 16. The charging of these condensers quickly reduces the current flow through the load to zero and likewise stops current flow through the tube 16 permitting it to deionize. The system has thus returned to the initial condition from which this description of its operation began; namely, both the tubes 5 and 16 are non-conductive and no current flows from the line wires 1, 2 to the load 3. The switch blade 9 may then be released to be held in the open-circuit position shown in the drawing by its bias arrangement previously described. One complete cycle comprising the initiation of current flow through the load 3, its maintenance for any desired period and its interruption by proper manipulation of the switch 9 has thus been described.

It will be noted that current flows through the tube 16 only during the transient period when current flow through the load is being reduced to the zero value. In most practical circuits the length of this transient period will be much less than one second, which is so small compared with those times during which a steady current flows through the load, or during which the load current flow is zero; that the life of the tube 16 under practical conditions should be enormous.

The resistors 11, 13 and 23 can be given relatively high values so that the currents which flow through them during the operations of the system described above are minute relative to the current through the load 3. The resistor 18 may likewise have such a value that the current flowing through it to the condenser 19 is small compared with the normal current through load 3, since the only function of resistor 18 is to permit the charging of capacitor 19 to nearly full voltage of the line 1, 2 during the periods that the load 3 carries steady currents. To give a typical example of the use of my invention, the voltage difference between the supply lines 1, 2 may be 300 volts, the load 3 may be designed to carry .075 ampere, the tube 5 (RCA884) may have a (plate) rating of 18 volts and .075 ampere; the tube 16 (RCA884) may have a rating of 18 volts at .075 ampere, the capacitor 19 may be of .25 microfarad; the capacitor 22 may be of .25 microfarad; the source 12 may be of 45 volts; the resistor 11 may have a value of 1 megohm, the resistor 13 may have a value of 1 megohm, the resistor 18 may have a value of 100,000 ohms and the resistor 23 may have a value of 100,000 ohms.

I claim as my invention:

1. In combination with a direct-current source, a load connected thereto through a gaseous discharge tube having a control electrode, a source of bias voltage and a resistor between said con-

trol electrode and its associated cathode, a manually operable switch connected between said control electrode and said cathode, a capacitor and a resistor in shunt with said load, a second grid controlled gaseous discharge device having its anode connected to the common terminal of the last-mentioned resistor and said capacitor and having a capacitor connected between its cathode and the cathode of the first-mentioned electrical discharge device, a connection through a resistor from the control electrode of the second-mentioned electrical discharge device to said bias battery, a switch connected between the control electrode of the second-mentioned discharge device and the cathode of the first-mentioned discharge device and a resistor connected between the cathode of the second-mentioned discharge device and the anode of the first-mentioned discharge device.

2. In combination, a direct-current source, a load having one terminal connected to the positive terminal of said source and its other terminal connected to the anode of a gaseous electrical discharge device provided with a control electrode, a connection between the negative terminal of said source and the cathode of said electrical discharge device, a bias source and a re-

5 sistor connected between the control electrode of said discharge device and its cathode, a single pole double-throw switch having one side connected in shunt to said source and the last-mentioned resistor, a resistor having one terminal connected to the positive side of said line and its other terminal connected to one terminal of a capacitor, the other terminal of said capacitor being connected to the anode of the above-mentioned electrical discharge device, a second electrical discharge device having its anode connected to the common terminal of the last-mentioned resistor and the last-mentioned capacitor and having its cathode connected through a capacitor to the negative terminal of said source, a resistor connected between the control electrode of said second discharge device and the common terminal of said bias source and the resistor previously specified as connected thereto, a connection between the grid of said second discharge device and the other side of said double-throw switch and a resistor connected between the anode of the first-mentioned electrical discharge device and the cathode of the second-mentioned electrical discharge device.

GEORGE W. NAGEL.
